UNITED STATES PATENT OFFICE

JOHN A. FROST, OF CARTHAGE, NEW YORK, ASSIGNOR TO NATIONAL PAPER PRODUCTS COMPANY, OF SAN FRANCISCO, CALIFORNIA, A CORPORATION OF CALIFORNIA

LOCK FOR PAPER CONTAINERS

Application filed November 14, 1927. Serial No. 232,964.

This invention relates to an interleaved paper container and dispenser and particularly to a locking mechanism therefor.

The object of the present invention is to generally improve and simplify the construction and operation of devices of the character described; to provide a container and dispenser for interleaved paper, such as paper towels, toilet paper, etc.; and to particularly provide a simple readily applied key actuated locking mechanism for locking the container so that it cannot be opened except by the attendant or one in possession of the proper key.

15 The invention is shown by way of illustration in the accompanying drawings in which:

Fig. 1 is a central vertical longitudinal section through the container and the locking mechanism,

20 Fig. 2 is a perspective view of the upper end of the back plate,

Fig. 3 is a perspective view of the key rotated plate,

25 Fig. 4 is a perspective view of the key,
Fig. 5 is a perspective view of the latching

mechanism of the lock,
Fig. 6 is a plan view of the same.

Referring to the drawings in detail and particularly Fig. 1, A indicates a rectangular channel which is divided into

39 lar-shaped back plate which is adapted to be secured to a wall or any other suitable support by means of screws or the like indicated at 2 and pivotally attached to the lower end

35 of the back plate as at 3 is a housing consisting of a front plate 4, side plates 5 and top and bottom plates as indicated at 6 and 7 respec-

tively. The housing forms a receptacle for interleaved sheets of paper such as indicated at 8 and they are removed one by one through an opening 9 and the bottom section 7 in the

an opening 9 and the bottom section 7 in the usual manner. The pivotal mounting of the housing permits it to be swung outwardly from the wall and the back plate A in the direction of arrow B.

15 direction of arrow *a* (see Fig. 1) when it is desired to insert a new supply of paper, but means are provided for preventing unauthorized

ized opening of the housing, the means employed being a locking mechanism generally indicated at B. This locking mechanism is best illustrated in Figs. 2 to 6 inclusive. The

lock proper consists of a plate 10 which is bent upon itself as indicated at 11. This plate is cut away as indicated at 12 to permit a pair of lugs 13 to extend upwardly through the same and the forward end of the plate terminates in a pair of hook-shaped latching members 14. The ends of the plate 10 are extended to form a pair of supporting lugs 15 and the forward edge of the plate 10 is extended to form a second pair of supporting lugs, as indicated at 15^a. The plate as a whole is preferably made of thin, cold-rolled sheet steel or the like as a certain amount of springiness is required, as far as the upper portion of the plate is concerned, i. e., sufficient flexibility is required to insure raising and lowering of the latch members 14. Mounted on the plate 10 as shown in Figs. 1, 5 and 6 is a substantially circular plate 16. This plate is provided with two small semi-spherical shaped projections 17 and 18, and its center portion is cut away to permit the formation of the lugs 13. The plate 16 is secured to the lower plate 10 by a rivet or the like as indicated at 19 and it is free to rotate about the same. On the upper portion of the latching mechanism shown in Fig. 5 is a cross bar 20 on which is formed two cam surfaces 17^a and 18^a. These cam surfaces are engaged by the projections 17 and 18 on the plate 16 when this is rotated, and the latches 14 are thus raised.

Formed on the upper end of the back plate (see Figs. 1 and 2) is a forwardly projecting flange 22 and formed in said flange is a pair of openings 23 through which the latches 14 are adapted to project. A cross bar 24 is formed at the lower edge of each opening 23 and the latches interlock therewith when the lock assumes a locked position, as shown in Fig. 1. The flange 22 is also cut away, as indicated at 25, this cut away portion being sufficiently large to allow ample space for the front supporting lugs 16 (see Fig. 5) of the plate 10. 95

In actual operation, it will be seen that a key is required to open the lock. This key is shown in Fig. 4. It consists of a head portion 26, a shank 27, a pair of side wings 28, and a point 29. This key is inserted through

a slot 30 which is formed in the upper part of the housing. When it is fully inserted, the point of the key enters the tubular rivet 19, while the wings 28 of the key will lie between the lugs 13. Hence, when the key is rotated 5 the wings of the key engage the lug 13 and the plate 16 will also rotate. During such rotation the projection 17 engages the cam member 17^a on the cross bar 20, the projection 18 and the cam member 18^a. The whole upper 10 plate, to-wit, the latches 14 and the cross bar 20 will thus be swung upwardly about the folded rear edge 11 and the latches will thus be raised out of engagement with the cross 15 bars 24. When this position is assumed, the lock is unlocked and the housing may be swung about the pivotal support 3 in the direction of arrow *a*, thus opening it sufficiently to insert a new supply of paper. The key 20 may be removed the moment the housing is opened and when it is refilled with paper and it is desired to close the same, it is only necessary to swing the housing towards the back plate A, as the latches 25 will then ride over the cross bars and will snap downwardly behind the same due to the inclined faces 31 presented.

The whole locking mechanism in reality is exceedingly simple as the number of parts 30 employed are only 3, i. e., the latching unit consists of a single plate 10 which is bent along the edge 11 to form the cross bar 20 and the latches 14. This forms one member of the lock. The second member is the rotating 35 plate 16, and the third member is the flange 22 formed on the back plate which carries the cross bars 24. The key is also simple as it merely consists of a head, a shank and a pair of wings. Neither the key nor the mechanism 40 is thus liable to get out of order, and furthermore, the simplicity of the structure permits rigid parts to be employed.

The latching unit shown in Fig. 5 may be attached to the top plate 6 of the housing in 45 any suitable manner, but as supporting lugs 15 and 16 are provided it is only necessary to punch them to secure the latching unit by means of rivets or the like.

While the lock mechanism has been described in conjunction with a container and dispenser for interleaved papers and the like, I wish it understood that its use should not be limited thereto, as it may be applied to numerous types of containers, boxes, covers, etc. 55 And further, I wish it understood that various changes may be resorted to within the scope of the appended claims. Similarly, that the materials and finishes of the several parts employed may be such as the manufacturer may decide or varying conditions or uses may demand.

Having thus described my invention, what I claim and desire to secure by Letters Patent is:—

65 1. The combination with a container hav-

ing a hinged cover section and a stationary section of a locking mechanism therefor, comprising a plate secured to the cover section and spaced therefrom, a resilient latch formed integral with the plate and lying between the plate and the cover, latch retaining means on the stationary section, and key actuated means whereby movement is imparted to release the latch with relation to the retaining means.

2. The combination with a container having a hinged cover section and a stationary section of a locking mechanism therefor, comprising a plate secured to the cover section and spaced therefrom, a resilient latch member formed integral with the plate and lying substantially parallel with said plate, in the space between the plate and the cover, latch retaining means on the stationary section, and key actuated means interposed between the latch and the plate whereby movement is imparted to release the latch with relation to the retaining means.

3. The combination with a container having a hinged cover section and a stationary section of a locking mechanism therefor, comprising a plate secured to the cover section, a latch member lying substantially parallel with said plate, a resilient connection between one end of the latch and the plate, a centrally pivoted plate interposed between the first-named plate and the latch member, a pair of lugs on said plate adapted to be engaged by a key to impart a rotary movement to the plate, and a projection on said plate engageable with the latch to release it with relation to the latch retaining member.

4. In a device of the character described, a plate bent back upon itself to form a resilient section, a pair of latch members on the free end of the resilient section, a second plate pivotally secured to the first-named plate and interposed between said plate and the resilient section of the plate, a pair of lugs on the rotary plate adapted to be engaged by a key to impart a rotary movement to the rotary plate, a cross bar connecting the latches and movable in unison with the latches, a pair of cam members on said cross bar, and a pair of projections on the rotary plate engageable with the cam members to raise and lower the latches with relation to the first-named plate.

5. In a lock of the character described, a rigid plate having a section thereof bent back upon itself to form a resilient plate, a pair of lugs formed on the rigid plate, one on each end thereof, a housing to which said lugs are secured, a latch member formed on the free end of said resilient plate, and a key actuated mechanism for moving the latch member to and away from the rigid plate.
